UNITED STATES PATENT OFFICE.

ANDREW WEMPLE, OF CHICAGO, ILLINOIS.

IMPROVEMENT IN THRASHING-MACHINES.

Specification forming part of Letters Patent No. 137,809, dated April 15, 1873; application filed June 15, 1872.

To all whom it may concern:

Be it known that I, ANDREW WEMPLE, of the city of Chicago, in the county of Cook and State of Illinois, have invented certain new and useful Improvements in Thrashing-Machines, of which the following is a full description, reference being had to the accompanying drawing making a part of this specification, in which—

Figure 1 represents a longitudinal vertical section; Fig. 2, a top or plan view with a portion of the upper thrashing-plate and cover and the top of the separator removed.

This invention relates to certain improvements in the machine patented to me April 23, 1872; and its nature consists in an improved construction of the thrashing-plates, in an improved arrangement of the fans, and in certain improvements in the separating and cleaning devices.

In the drawing, A represents the bed-frame, mounted upon a suitable carriage; B, cross-ties, and also bottom plate of the thrashing-chamber; C, uprights forming part of the frame-work, and supporting the sides of the thrashing-chamber; D, lower thrashing-plate; E, feeding-board; F, feeding-tables; G, upper thrashing-plate; H, fan and fan-case; I, wind-board; J K, sieve; L, wire rods standing over the sieve; M, similar rods over the board J, forming part of the sieve; N, shaft for revolving the carrying-belt O; P, board behind the front portion of the belt O; Q, endless apron or straw-carrier; R, separator-case; S, adjustable spout; T, grain-board; U V, hinged boards or valves for regulating the draft into and through the separator; W, platform for attendant or driver; X, shaft for driving the thrashing-belt, mounted with suitable pulley or gear wheels for operating the machine; Y, rods or spurs on the periphery of the revolving thrashing-plate.

The frame-work of the machine is made of wood, and the other parts of iron or other suitable material. The revolving thrashing-plate D is made conical in form, and is provided with thrashing-teeth only at or near its outer edge. The stationary plate G is made of a corresponding form—the opening or space between the

two increasing toward the center—and is provided with thrashing-teeth at or near its outer edge. One row of teeth on the revolving plate and two on the stationary plate, or two on one and three on the other, may be used; the least number of teeth that will do the thrashing are preferred, for the reason that as the number of teeth are increased the feeding of the straw through the thrasher is impeded. The stationary plate G is provided at the front with a depression or feeding-board, E, to facilitate feeding, and at the sides of said depression with one or more feed-tables. The case surrounding the thrashing devices is provided with an opening at Z, through which the straw and grain are discharged into the separator Z'. Below this case I place a fan-case, H, with a suitable fan, from which I direct a blast into the lower part of the separator. By means of this fan I can regulate the blast of the thrashing-case, and it enables me to use a lighter blast in said case; it also divides the currents in the separator so that the grain is less liable to be blown over or pass out with the straw. The straw and grain, passing into the separator at Z, fall on the rods M, where they take a part of the blast; from thence onto the board J and sieve K, where they take the remaining portion of the fan-blast; the principal portion of the grain passes through the sieve into the spout A'.

To prevent the straw from accumulating in the bottom of the separator I provide an endless belt, O, which is mounted on suitable carrying-rollers, and provided with hooks, pins, or other projections to carry up the straw. This belt is inclined toward the top, as shown, so as to allow any grain that may be caught in the straw or thrown in by the operation of the machine to fall out. I usually make this belt in strips and place it behind the board P, as shown, to prevent the grain from passing to the back of the separator. The straw carried by the blast up this belt or series of belts passes over the shaft N onto the endless belt Q, which is also preferably made in strips, and out at the spout S. The spout S may be hinged so as to be raised or lowered by any suitable device.

At the top of the separator I place an adjustable board, T, by which the blast in the discharge-spout is regulated, and which catches any grain that may pass over the shaft N and directs it downward. Any grain which may fall through the belt or series of belts Q will pass to the bottom of the spout, and from thence fall to the bottom of the separator into the spout A'. The valves or boards U V perform the same office in this as they do in the machine heretofore patented to me. The rods or bars Y occupy the place of the triangular fans shown in the patent to me April 23, 1872. They may be made, however, of round or square rods, and I usually apply six of them. I have found them to be sufficient to discharge the straw from the thrashing-case.

What I claim as new is as follows:

1. The combination of the thrashing-plates D and G and fan-rods Y with the feed-table or opening E and tables F, substantially as specified.
2. The combination of the fan H with a sep-

arating-chamber and the thrashing-plates D and G and their case, substantially as and for the purposes specified.

3. The carrier O, in combination with a separator, substantially as and for the purpose specified.

4. The combination of the sieve K, inclined carrier O, and carrier Q, substantially as described.

5. The combination of the rods M and L, sieve K, and wind-board I with the carriers O and Q in a separator, constructed substantially as specified.

6. The back board P, when located and operating substantially as and for the purpose specified.

7. The blast-fan H, in combination with the separator Z', constructed and operating substantially as specified.

ANDREW WEMPLE.
